UNITED STATES PATENT OFFICE.

GEORGE H. REIMER, OF FULTON, ILLINOIS, ASSIGNOR TO PATENT NOVELTY COMPANY, OF FULTON, ILLINOIS, A CORPORATION OF ILLINOIS.

HOLDING DEVICE.

Application filed February 23, 1922. Serial No. 538,491.

To all whom it may concern:

Be it known that I, GEORGE H. REIMER, a citizen of the United States, and a resident of Fulton, county of Whiteside, and State of Illinois, have invented a certain new and useful Improvement in Holding Devices, of which the following is a specification.

This invention relates to sheet metal devices formed to hold various articles, such as 10 ice-picks and coupon books, whereby the same will be retained in convenient position for use.

Generally stated, the object of the invention is to provide an improved construction 15 and arrangement whereby the entire device may be formed from a single piece of sheet metal, with separate pockets or compartments for the ice-pick and coupon book or other articles, and whereby the device may 20 be produced by comparatively simple and inexpensive operations in the manufacture thereof.

Another object is to provide an improved construction and arrangement whereby certain 25 features of construction heretofore employed are not necessary.

To this and other useful ends the invention consists in matters hereinafter set forth and claimed and shown in the accompanying 30 drawings in which—

Figure 1 is a perspective of a combined ice-pick and coupon book holder embodying the principles of the invention, showing the same attached to a support in position for 35 the easy and convenient withdrawal of the ice-pick or coupon book, or any other articles which the device may be adapted to hold.

Figure 2 is a view looking down upon the upper end of said device.

Figure 3 is a side elevation of said device.

As thus illustrated, the invention comprises a single piece or section of sheet metal bent or pressed into the desired form to 45 provide a flat front wall 1 which is inclined outwardly to provide a pocket 2 for the coupon book. Said pocket is provided with downwardly tapered side walls 3, as shown, and spaces 4 are formed outside of these 50 side walls, whereby the ice-pick pockets 5 are spaced a distance from the coupon book pocket. In other words, these ice-pick pockets are formed by downwardly 55 tapered side walls 6 and 7, and by curved outer walls 8, whereby the walls 3 and 6 and

the spaces 4 intervene between the coupon book pocket and the two ice-pick pockets. Side ears 9 are preferably formed at the upper corners of the device, with holes 10 for the insertion of nails or screws to attach the device to the wall or other support in position for the convenient insertion and removal of the ice-pick or coupon book or other articles. The lower edge of the device is formed with an ear 11 having a hole 12 for 65 the insertion of a nail or screw for attaching purposes. In this way the side edges and the bottom edge of the device are pressed tightly against the wall or other surface, so that only the upper ends of the three pockets 70 are open. Preferably, as shown, a horizontal rib or bead 13 is formed just below the upper edge 14 of the front inclined wall 1, thereby to stiffen the sheet metal. Thus the wide middle pocket is separately formed 75 from the two narrow or outer pockets, the metal which forms the latter having nothing to do with the formation of the wide middle pocket. The spaces 4, as previously 80 explained, are interposed between the sides of the middle pocket and the inner sides of the outer pockets, whereby each pocket is distinct and separately formed from the body of sheet metal. The rounded inner walls 15 form stiffening ribs which are interposed 85 between the wide pocket and the narrow pockets and bear against the wall or other flat surface to which the device is attached. With this construction, the screws or nails 90 for attaching the device in place, so that its marginal edges will rest against the flat surface, do not pass through any of the pockets, but to the contrary are all inserted at 95 points outside of the area of said pockets, in the manner shown and described. It will be seen that side walls 3 and 6 and 7 are all flat and disposed in vertical planes, so that they are parallel, whereby the front walls 8 are each as wide at its lower end as at the upper end thereof, notwithstanding that 100 the pockets 5 taper toward their lower ends when the device is viewed from the side, as shown in Figure 3, and this also means that the wall 1 is as wide at its lower end as at the upper end thereof.

It will be seen that the construction provided forms a pair of hollow inner rounded stiffening ribs at 15 which engage the back wall surface but are not attached thereto, 110 and a pair of hollow outer rounded stiffen-

ing ribs at 8, thus stiffening the thin sheet metal structure in a beneficial manner, and at the same time providing the two narrow vertical grooves 4 which face outwardly 5 and which separate the two narrow pockets from the broad middle pocket. The outer portions 9 resist any outward pressure on the front wall of the wide middle pocket, and the unattached inner ribs 15 thus interposed 10 between the carrying pockets are broadly new.

What I claim as my invention is—

1. In a device for holding an ice-pick and a coupon book or other articles, the combination of an outwardly inclined front wall of sheet metal, with downwardly tapered side walls forming with said front wall a relatively wide pocket, and other downwardly tapered side walls connected by narrow outer front walls to form relatively narrow pockets forming hollow rounded outer stiffening ribs at each side of said wide pocket, with outwardly open narrow spaces forming narrow vertical open grooves on the outer face of the device between the middle pocket and the two narrow pockets, marginal attaching portions for the upper corners of the device, adapted to engage a wall or other flat surface, when the device is at-

tached in position for use, and inner narrow walls unattached to said surface and forming hollow rounded inner stiffening ribs between said pockets to merely engage said flat surface, so that outward pressure on the front wall of said wide pocket is resisted entirely by said outer attached corner portions, and whereby said pockets are all closed at the back of said device by said flat surface and are each separately formed and open only at the upper edge of said device. 40

2. A structure as specified in claim 1, said attaching provisions comprising holes formed outside of the area of said pockets, adjacent the outer edges of said device, with a margin of sheet metal provided at the sides 45 and lower edge of said device for the formation therein of said holes.

3. A structure as specified in claim 1, said outer pockets each having their side walls disposed parallel, so that the outer rounded wall of each inner pocket is as wide at its lower end as at the upper end thereof. 50

4. A structure as specified in claim 1, the side walls of each pocket being flat and all of these side walls being vertical and parallel. 55

GEO. H. REIMER.
